FORMING DIE FOR INTAGLIO PRINTING PLATES

John H. Bender, Kansas City, Mo., assignor to
Inter-Collegiate Press, Kansas City, Mo., a corporation of Missouri

Application August 1, 1938, Serial No. 222,388

2 Claims. (Cl. 153—3)

This invention relates to the art of manufacturing printing plates and more particularly to the art of manufacturing engraving plates for intaglio printing machines such as shown and described in United States Letters Patent No. 2,053,510, issued Sept. 8, 1936, and owned by the assignee of this application.

One of the important aims of the instant invention is the provision of a forming die for intaglio printing plates that is in the nature of the equipment shown and described in United States Letters Patent No. 2,090,096, issued Aug. 17, 1937, and which is also owned by the assignee of this invention and application.

The engraving of calling cards or the like on machines employing individual printing plates becomes more efficient when the indicia bearing portion of the plate is formed on an elevated, longitudinally and transversely arched boss which permits wiping off of surplus ink without having to clean a large area. The printing plate per se therefore, which is made in accordance with this invention, not only has the offset portions near the ends thereof, but has a body that is longitudinally and transversely arched, and which is embossed to create a similarly arched surface on one side of the plate upon which the engraving is formed.

This invention also contemplates the employment of novelly arranged and sized backing member positioned on the printing plate with respect to said boss so that the forms of the plate may be accurately accomplished in one operation through the use of specially constructed equipment.

A yet further aim of the instant invention is the provision of a forming die for printing plates of the aforementioned character wherein is employed a pair of relatively movable forming members, one of which is provided with a facing of resilient material against which the other member forces the plate being formed.

A large number of minor objects will appear during the course of the following specification, referring to the accompanying drawing wherein:

Figure 1 is a fragmentary side elevation of a forming die assembly made in accordance with the present invention.

Fig. 2 is a top plan view of the lower forming member and parts associated therewith.

Fig. 3 is a vertical fragmentary sectional view through the die assembly taken on line III—III of Fig. 1, and looking in the direction of the arrow.

Fig. 4 is a similar sectional view but with the forming members moved together.

Fig. 5 is a face view of the printing plate in the blank form.

5 Fig. 6 is an edge elevation of the printing plate in the condition shown in Fig. 5.

Fig. 7 is an edge elevation of the printing plate illustrating its condition after formation.

10 Fig. 8 is an enlarged cross sectional view through the plate prior to forming, taken on line VIII—VIII of Fig. 6; and

Fig. 9 is a similar view through the formed plate taken on line IX—IX of Fig. 7.

The forming die wherein the plate embodying this invention may be given the desired contour, comprises a stationary shoe 12 having guide blocks 14 and 16 integral therewith between which the lower forming member 18 is mounted for vertical reciprocating movement.

15 Stops 20 on forming member 18 travel toward and from shoulders 22 formed by blocks 14 and 16, and cushioned springs 24 yieldably maintain stops 20 against shoulders 22 when the device is not in operation. Springs 24 have their ends 20 engaged in sockets 26 and 28 provided in members 18 and 12 respectively, and the downward movement of member 18 is limited when its lower edge 30 strikes surface 32 of shoe 12.

20 A gauge face 34 and shoulder 36 bear against one end of plate 38 when it is first introduced into the die for forming. A maintaining spring 40 bears against the other end of plate 38 to hold the first mentioned end thereof against face 34.

Member 18 has its upper surface 42 both longitudinally and transversely arched as illustrated in Figs. 1, 3 and 4. A facing of resilient material 44 overlies the arched surface 42 of member 18 for the very important purpose which will be hereinafter fully set down.

25 40 The complementary forming member 46 which is above member 18 has a longitudinally and transversely arched surface 48 which acts with surface 42 of member 18 to impart the desired contour to plate 38. This upper forming member 46 is mounted upon a reciprocating ram 50 that may be moved up and down through the application of any suitable force.

The forming member 46, ram 50 and outwardly extending arms 52 are yieldably maintained at the upper end of a path of travel by springs 54. A bearing 56 journals ram 50 and ear 58 engages surface 60 of bearing 56 when member 46 is at one end of its path of travel.

55 Ear 62 extends rearwardly from member 46 and engages surface 64 on shoe 12 when member

46 is at the other end of its path of travel. Ear 62 does not bear upon surface 64 until after surface 30 has engaged surface 32 to completely stop the downward movement of member 18.

The plate 38 is made by first producing a flat blank from copper of suitable thickness and size. The ink receiving die 66 is engraved on one side of plate 38 as illustrated in Fig. 5, and then a back member 68 is secured to the other side of plate 38 in direct opposition to the area covered by indicia 66.

When plate 38 is introduced into the die in a manner illustrated in Fig. 1, the downward movement of upper forming member 46 forces plate 38 against the upper surface of forming member 18 to thereby longitudinally and transversely arch the same. As forming members 18 and 46 move downwardly together, the end of plate 38 overlying shoulder 36 is abruptly bent to create the offset portion 70 which is necessary when using the plate in machines disclosed in the aforesaid patent. The other end of plate 38 is slightly offset by ear 72 as the forming members approach the lower end of their path of travel.

The facing of resilient material 44 has an inherent rigidity sufficient to support plate 38 while it is longitudinally and transversely arched. This arching action is complete when lower forming member 18 has arrived at the end of its path of travel in one direction and has been arrested by the interengagement of surfaces 30 and 32. Ear 62 of member 46 has not yet arrived at a point where it engages surface 64 and therefore, the downward movement of upper forming member 46 continues until arrested by the interengagement of ear 62 and surface 64.

During this continued movement on the part of upper forming member 46, the backing member 68 which is interposed between the upper side of plate 38 and the face of member 46, creates a boss commensurate in size with the area of member 68 and which is likewise arched in both directions as is plate 38. The surface 74 of this boss bears the indicia 66 and the remaining part of plate 38 is below surface 74. This backing member 68 should be a strong material, such as fibre, so that the downward force exerted thereagainst by member 46 will be sufficient to further arch and emboss plate 38 and to force the embossed portion thereof against the facing of resilient material 44 to compress a portion thereof and thereby permit so forming the plate.

When the completed plate is mounted in the machine for use, the fibre backing member may

be entirely removed for the strength of the material from which plate 38 is formed, is sufficient to maintain the contour imparted thereto throughout any normal run.

Plates 38 which are formed as hereinabove set down, will permit operating intaglio printing machines at a higher rate of speed. The finished product is of high quality for the stock that is printed is placed under greater pressure only at the area thereof which receives the ink.

It is conceivable that forming dies for printing plates may be made to present different physical characteristics than those illustrated and described, but so long as the printing plate created is in the nature of that herein disclosed, the spirit of the invention is involved, and it is desired therefore, to be limited only by the scope of the appended claims.

Having thus described the invention, what is claimed as new and desired to be secured by Letters Patent is:

1. A forming die for printing plates comprising a pair of relatively movable forming members arranged to engage the plate therebetween as they are moved together; a facing of resilient material on one of the members; a stop to limit the movement of one of the forming members as the other member approaches the same to form the work; and a stop to limit the movement of the other forming member after it has moved toward the one member a short distance after the one member has reached the limit of its movement said forming members each having their plate engaging faces longitudinally and transversely arched.

2. A forming die for printing plates comprising a lower forming member; an upper forming member; resilient means for holding the lower forming member at one end of a path of travel; stops for arresting movement of the lower forming member at the other end of its path of travel; means for moving the upper forming member toward the lower forming member to form the work; a stop to limit the movement of the upper forming member toward the lower forming member; and a facing of resilient material on one of the forming members, said forming members each having their plate engaging faces longitudinally and transversely arched, said stops for the lower forming member being disposed to arrest its movement in one direction before the stop arrests the movement of the upper forming member in the same direction.

JOHN H. BENDER.
